UNITED STATES PATENT OFFICE.

ALCIDE C. DROZ AND HENRY PERRET, OF ST. IMIER, SWITZERLAND.

DESIGN FOR WATCH-MOVEMENT.

Specification forming part of Design No. 7,136, da'ed January 27, 1874; application filed September 12, 1873.
[Term of Patent 14 years.]

To all whom it may concern:

Be it known that we, ALCIDE CONSTANT DROZ and HENRY PERRET, of St. Imier, Canton of Berne, Switzerland, have invented a Design for Watch-Movement, of which the following is a specification:

Figure 1, in the accompanying drawing, represents a back view of the works of the watch. Fig. 2 is a section on the line *c c*, Fig. 1.

Similar letters of reference indicate corresponding parts in all the figures.

The design consists in a new shape of the cocks or plates on the back of the works of a watch. On the back are five plates or cocks, as shown in Fig. 1.

The plate A is made almost of the shape of a curvilinear triangle, with two concave sides, *a* and *b*, and a convex side, *x*. The sides *a* and *b* meet in an almost circular enlargement, *d*, of the plate A, in which enlargement the spindle of the escapement-wheel is hung. The side *a* has the same curvature as the circumference of the balance-wheel, and is placed parallel thereto, while the side *b* has a shorter radius, and is also shorter, than the side *a*. The side *x* forms a part of the circumference of the watch-works. The cock B has somewhat the shape of the cross section of a double concave lens, the two concave sides *e* and *f* meeting, at their inner ends, two semicircular projections, which form supports for the

spindles of two of the toothed wheels of the works. The convex side *i* forms a portion of the circumference of the works. The plate C, which covers almost half the back of the watch, and under which the mainspring is situated, is bounded by a semicircular outer side, *j*, in line with the circumference of the works. The plate is further bounded by a short, straight line, *k*, and by an ogee-side, *l*, these two sides being connected by a concave side, *m*, which meets *l* at a point, *o*. Above, and partly covering, the cock C is placed the cock D. The same has a convex side, *p*, two straight sides, *q* and *r*, and three concave sides, *s*, *t*, and *u*.

The fifth cock E is made of the usual shape, and does not form part of this invention.

We claim as our invention and desire to secure by Letters Patent—

The design for a watch-movement, consisting of the arrangement of the plates A, B, C, and D, formed as described, and represented in the drawing.

In testimony whereof, we have hereunto signed our names this 4th day of July, 1873, before two subscribing witnesses.

ALCIDE CT. DROZ.
HENRY PERRET.
